UNITED STATES PATENT OFFICE.

JOHN SCOTT TAYLOR, OF CLAREMORE, INDIAN TERRITORY.

DESIGN FOR A SLIDING JAW FOR PIPE-WRENCHES.

SPECIFICATION forming part of Design No. 31,140, dated July 4, 1899.

Application filed June 8, 1899. Serial No. 719,850. Term of patent 7 years.

To all whom it may concern:

Be it known that I, JOHN SCOTT TAYLOR, a citizen of the United States, residing at Claremore, in the Cherokee Nation, Indian Territory, have invented a new and original Design for a Sliding Jaw for a Pipe-Wrench; and I do hereby declare the following to be a full, clear, and exact description of the invention, such as will enable others skilled in the art to which it appertains to make and use the same.

This invention relates to a new and useful design for the inner or sliding jaw of a pipe-wrench.

15 In the accompanying drawings, Figure 1 is a side elevation of my design. Fig. 2 is an end view. Fig. 3 is a front elevation thereof.

Referring to parts in said figures by letters of reference, A is the jaw, straight or right lined upon its front and lateral portions and gradually curved forward toward said front, as at a, and from thence straight or right lined, as at a'. Through jaw A is a passage

B, rectangular in its general contour and having its upper and lower walls slightly inclined forward toward the front, as at a^x. Beyond a' the jaw A is curved or concaved rearward and slightly outward, as at a², thence rounded, as at a³, and again curved or convexed forward, as at a⁴, and finally to the forward 30 straight or right lined edge of the jaw, thus providing the latter with a horn-like or curved arm, as shown.

Having thus fully described my invention, what I claim as new, and desire to secure by 35 Letters Patent, is—

The design for an inner or sliding jaw for a pipe-wrench, substantially as herein shown and described.

In testimony whereof I affix my signature 40 in the presence of two witnesses.

JOHN SCOTT TAYLOR.

Witnesses:

J. LIN COMER,
JOHN DIRICKSON.
